BINDER

Application February 11, 1946, Serial No. 646,874

2 Claims. (Cl. 129—8)

1

This invention relates in general to a binder for loose sheets, booklets, and the like, and is more particularly described as a spring expansion binder for releasably and flexibly binding sheets and the like in a cover.

An important object of the invention is in the provision of a resilient spring binder which allows the sheets or booklets to be spread flexibly at the binding so that a book thus bound will lie open more readily upon a plane surface, will remain in open position, and will disclose more reading material close to the binding.

Further objects of the invention are to provide improved means for attaching the flexible binder to a cover; to provide a resilient binding attachment for any association of loose leaves to be attached together; to provide a resilient holder for separating a part of the loose leaves for inserting other leaves therebetween; to provide improved means for expanding or contracting the binder; to provide an improved locking attachment for a binder of this kind; to unite and combine two or more resilient coil springs to form a loose leaf binder; and in general to produce the construction herein shown and described.

A preferred exemplification and embodiment of the invention is illustrated in the accompanying drawings in which

Fig. 1 is a part sectional view of a binder in accordance with this invention as applied to a plurality of sheets included in a loose leaf cover;

Fig. 2 is a top view of the locking plate structure shown in Fig. 1;

Fig. 3 is a perspective illustrating the use of the take-off sleeve; and

Fig. 4 is a sectional view illustrating the spring action of the binder for supporting a book in flat open position.

In the loose leaf binders now commonly employed, having binding rings or fixed posts included between spaced ends, the sheets or pamphlets therein are easily separated and held apart for reading, even close to the binding, when the rings or posts are not crowded. With the post type, even if the booklet is not filled, relatively stiff sheets do not remain in open position when the book is placed with its covers on a flat surface. But when these binders are crowded or are tightly filled with books or leaves, it is practically impossible to open them sufficiently for reading near the binding edge, a book will not remain open if placed with its back on a flat surface, and the leaves will tend to flop closed, losing the reader's place, unless the book is held in open position.

2

The present invention is designed and intended to overcome the above objections and to provide a spring expansion binder which may be enlarged or decreased simply by threading one resilient part into another resilient part; being resilient, it will remain in open position when the book is placed upon a flat surface because the binding post will spread in an arc which permits the leaves at each side of the open point to lie and remain in open position and also to spread the leaves apart at the binding so that the reading matter of each page is easily seen, even down to the binding itself. This is of considerable advantage because many sheets, booklets, and the like, not originally intended for binding, are placed in loose leaf books by others for the purpose of filing or keeping them in order, it being necessary then to perforate the booklets near the binding thereof for inserting the binding devices of a loose leaf binder therethrough.

Referring now more particularly to the drawings, this invention is explained more particularly in connection with a binder having stiff covers 6 joined by a flexible back 7 and with binding flaps 8 flexibly attached to the inner ends of the covers. It is desirable to releasably hold a variable number of sheets or pamphlets 9 in such a cover, the pamphlets usually increasing in number to tax the capacity of the binder.

30 The pamphlets 9 are provided with perforations 10 to register with perforations 11 in the binding flaps 8 and attaching means is applied thereto for binding them resiliently together.

This resilient binding comprises two hollow 35 tightly wound cooperating spirally wound spring sections 12 and 13, one being of a size to fit tightly so that it may be threaded into the other, the spiral winding of the wire forming the springs also forming spiral threads upon which one section is threaded into the other. At the end of one member, as 13, is an enlarged head 14 formed of the same wire wound spirally in the same plane. At the end of the other member 12 is a similar head 15. By inserting these spring sections 12 and 13 through the flaps 8 from opposite sides and through the perforations 10 of the pamphlets, and then by threading the section 12 within the section 13 the book and the binding may be varied as desired within the limits of the members, the engagement of only a few turns of one member within the other being sufficient to hold the binding members together.

In opening the binding to admit new sheets it is frequently desirable to insert a sheet or 55 pamphlet at the center of or between separated

portions 9a and 9b as shown in Fig. 3. For this purpose a sleeve 16 of spirally wound wire having an enlarged head 17, may be provided which loosely surrounds both of the spring sections 12 and 13 but is disposed adjacent the smaller section 12 so that when the sections 12 and 13 are disconnected the sleeve 16 may be removed with the upper group of pamphlets 9a as shown in Fig. 3 without separating them, a sheet or sheets being then easily applied to the projecting posts 13 and the sheets remaining thereon. This sleeve is then included with the binding, the head 17 being disposed between the outermost sheet and one of the flaps 8 and held in place until another similar addition or withdrawal of sheets is necessary. As it does not engage the threads of either of the members 12 and 13, it does not interfere with the flexible bending of the binding as illustrated in Fig. 4.

In order to releasably hold the binding post members in place a clamping plate 18 may be provided for each one with a pivot 19 for rotatably attaching it to the flap 8 adjacent. In this plate is a slot 20 curved inwardly from one edge about the pivot 19 as a center and of a width to closely embrace the spiral stem portion of one of the members 12 below the head 15 thereof. At opposite sides of the slot are projections 21 struck up from the plate and having inclined faces 22 at the outer sides which engage the under side of the head 15 and tend to tightly engage it and the convolutions of the head as the plate is pressed in a direction to engage the slot 20 with the stem. When the locking plate is thus engaged the stem will not be easily disconnected therefrom as the plate 18 must be pressed to disengage the projection 21 from the head 15.

In any position the clamping plate does not interfere with the spring action of either of the post sections 12 or 13 and when a book with a binding of this kind is placed open on its back the covers will lie flatly upon a plane surface as indicated in Fig. 4, the post sections flexing in the form of an arc or curve and the turns thereof even opening up slightly and spreading apart, depending upon the thickness or weights of the sections of the book at opposite sides of the opening. Thus the book will tend to remain open with the innermost leaves spread apart so that it is easily possible to see any printed matter, even down to the binding posts, and between the binding posts down to the binding or inner edge of the sheet itself, which is sometimes an advantage in reading the booklets or pamphlets bound therein.

If desired a spring lock washer 23 may be applied over the spring section 13 and against the inner side of the flap 8 through which it is inserted if it is desired to hold this section with its head in contact at all times with the outer side of its flap. The spring washer engages the outer convolutions or threads of the spring wire

surface 13 and preferably may be disengaged from the spring section 13 by threading it out of the washer at any time if desired.

I claim:

1. In a binder for perforated loose leaf sheets, comprising a pair of covers having foldable perforated flaps, a pair of headed resilient spiral wire post sections inserted from the opposite sides through the perforated flaps so that their heads engage the inner sides of the flaps when they are folded inwardly and the stems are inserted together with a threading movement, fastening means comprising a lock washer applied over one spring section and against the side of the flap opposite the head of the section to hold this section in contact with the flap, and a locking plate for the other section pivoted to the flap of the cover and having an arcuate slot therein to embrace the stem of the headed member and having projections at the sides of the slot for engaging the under side of the head for releasably locking it in place in the slot, the plate being disengageable from the head so that that post section may be rotated into and out of the other relatively fixed post section.

2. A binder for a plurality of loose perforated sheets, comprising a pair of flexible spirally wound wire tubes each having a unitary flat spiral head at one end, the binder having perforated flaps through which the stems of the tubes are inserted oppositely, the heads engaging the flaps at the relatively outer sides thereof and the inner ends of the tubes being threaded one within the other, means in connection with one of the flaps for holding the spirally wound head in connection with its flap, means in connection with the other spirally wound tube for releasably engaging the head of the other spirally wound tube, and a spirally wound shell with a unitary flat spiral head at one end larger in diameter than both of the tubes inserted through the loose sheets and projecting over the extremity of the outermost spirally wound tube which telescopes over the other tube engaged thereby, the head of the shell engaging the inside of the flap which is releasably attached to one of the wire tubes so that a plurality of sheets may be removed with the sleeve when the binder is open keeping the sheets together for replacement upon the posts when the binder is closed.
